UNITED STATES PATENT OFFICE.

MAX F. BIERND, OF MIAMI, FLORIDA.

EGG CONTAINER.

1,416,934.

Specification of Letters Patent. Patented May 23, 1922.

Application filed July 2, 1921. Serial No. 482,210.

To all whom it may concern:

Be it known that I, MAX F. BIERND, a citizen of the United States, residing at Miami, in the county of Dade and State of Florida, 5 have invented certain new and useful Improvements in Egg Containers, of which the following is a specification, reference being had to the accompanying drawings.

This invention relates to egg containers, 10 and has for its object to provide a container or pocket for each egg, so constructed that any quantity of the containers may be packed in a box or shipping crate without placing packing or like cushioning means between 15 the containers, or separating the containers in any manner.

It is another object of the invention to provide a container in the form of a resilient pocket for suspending the egg within 20 a shipping crate.

It is also an object of the invention to provide a device of this character wherein the jaws of the resilient pocket and the support of the jaws are formed from a single sheet 25 of material, the ends of said jaws being connected to each other.

It is a further object of the invention to provide a container of this character including a resilient pocket or jaw members, so arranged that when the egg is engaged with the bottom of the pocket, the upper portions 30 of the pocket are urged into engagement with the egg.

With these and other objects in view, the 35 invention consists in the improved construction and arrangement of parts to be herein-after more particularly described, fully claimed and illustrated in the accompanying drawings, in which:

40 Figure 1 is a longitudinal sectional view of an egg container, constructed in accordance with an embodiment of the invention.

Figure 2 is a top plan view of the pocket or container,

45 Figure 3 is a plan view of the blank from which the pocket is formed,

Figure 4 is a fragmentary sectional view, showing the means for connecting the ends of the collar, and

50 Figure 5 is a view showing the manner of packing the containers in a shipping crate.

Referring to the drawings, 7 designates a container substantially in the form of a resilient pocket, said pocket consisting of 55 a strip 8, having a plurality of jaws 9 projecting from one of its longitudinal edges,

said jaws being spaced from each other, and are of a length to permit the ends thereof to be disposed centrally of the strip when the strip is formed into a support. 60

The end portions 10 and 11 of the strip are intended to be connected to each other by means of a staple 12, as shown in Figure 4, so as to form a collar or support for the pocket. Each of the jaws 9 is extended upwardly from the longitudinal or upper edge of the collar or support as at 13, and then extended downwardly as at 14, and then inwardly as at 15, toward the center of the collar. It will be noted that each of the 65 jaws inclines inwardly toward the center of the pocket, so that a resilient loop 15^a is formed substantially at the junction of the portions 13 and 14 of the jaws. By this arrangement, the ends of the jaws meet at 70 the center of the pocket, the end of one jaw being adapted to engage the confronting end of the opposite jaw. The ends of one pair of jaws are disposed upon the ends of the remaining pair of jaws, and said ends 75 are secured to each other by means of staples 16. A resilient pocket is thereby formed, which conforms to the shape of the egg and is capable of preventing damage to the egg, regardless of the misuse or handling of the 80 shipping crate A. When the egg is inserted in the pocket, the junctions of the portions 13 and 14 of the jaws are moved toward the egg upon contact of the end of the egg with the connected ends of the jaws, so that 85 a clamping action takes place, and while this clamping action prevents accidental disengagement of the egg from the pocket, it does not interfere with the yieldable movement of the pocket. 90

When packing the eggs within the shipping crate A, the layers of pockets containing the eggs are disposed one upon the other, a sheet of cardboard B being disposed between each layer, said sheets forming the 100 top and bottom portions of the containers or pockets. At the end of each layer, is a filler C of any suitable material, the fillers alternating at the end of each layer so as to properly position the containers of one 105 layer between the containers of the adjacent upper and lower layers. In this way, the loop portions 15^a serve to support the adjacent layers of containers, and at the same time prevent the egg within the pocket 110 from coming in contact with the upper cardboard sheet. The use of the cardboard sheet

between the layers does not interfere with the yieldable movement of the pocket, as the cardboard is not connected in any manner to the upper ends of the containers, and the 5 weight of the egg serves to draw the jaw members inwardly. By the novel position of the pocket, the egg does not at any time come in contact with either the upper or lower layers, but is suspended therebetween. 10 Furthermore, in view of the fact that the portions 14 of the pockets are inclined inwardly, there is no danger of the same coming in contact with the jaws or similar portions of the adjacent pockets when placed 15 within the shipping crate.

It is of course obvious that I do not desire to be limited to the precise arrangement of the jaws and pocket, as the pocket may be constructed or formed V-shaped or 20 U-shaped, and the container made in various shapes without departing from the spirit of the invention.

From the foregoing, it will be readily seen that this invention provides a novel form of 25 egg container which insures the safe delivery of any quantity of eggs by providing a separate container for each egg and preventing the egg from being crushed, and also from coming in contact with any object, 30 and while the egg is yieldably supported, the resilient force of the container is sufficient to prevent the egg from coming in contact with the adjacent containers, so that damage is eliminated.

35 What is claimed is:—

1. An egg container embodying a supporting member, arms carried by and extending from said supporting member, and a resilient container suspended between the 40 arms in spaced relation to the body member.

2. An egg container of the character described comprising a body member, egg holding means within said body member, 45 said means comprising resilient strips, each

strip being bowed adjacent their intermediate portions to provide parallel arms, the end portions of said arms being extended inwardly toward and secured to each other to form a pocket.

3. An egg container of the character described comprising a body member, egg holding means carried by said body member, said means consisting of yieldable strips, each strip being extended back upon itself 55 to provide parallel arms, the end portion of each arm being extended inwardly toward the opposite arm, the ends of the arms being disposed substantially at right angles to the strip, and means for connecting the 60 ends of the arms to each other.

4. An egg container of the character described consisting of a strip of material having its ends connected to form a collar, a plurality of strips extending from the upper edge of the collar, each of said strips being extended back upon itself and then inwardly toward the opposite strip to substantially provide a pair of U-shaped jaw members, the ends of said strips being secured to each other centrally of the collar.

5. An egg container of the character described consisting of a strip of material having its ends connected to form a collar, said collar having two pairs of arms projecting 75 from its upper edge, each of said arms being extended inwardly toward the center of the collar, and then downwardly substantially in parallel relation to the inwardly extending portion of the arm, and then inwardly toward the opposite arm of the pair, the end portions of one pair of arms being disposed upon the end portions of the remaining pair of arms, and means for securing the end portions of each pair of arms to 85 the end portions of the remaining pair of arms.

In testimony whereof I hereunto affix my signature.

MAX F. BIERND.
